UNITED STATES PATENT OFFICE.

GEORGE F. CARD, OF THREE RIVERS, MICHIGAN.

RECORDING DEVICE.

962,492.

Specification of Letters Patent: Patented June 28, 1910.

Application filed September 21, 1905. Serial No. 279,443.

To all whom it may concern.

Be it known that I, GEORGE F. CARD, a citizen of the United States, residing at Three Rivers, in the county of St. Joseph, 5 State of Michigan, have invented certain new and useful Improvements in Recording Devices, of which the following is a specification.

This invention relates to improvements in 10 recording devices.

The objects of this invention are, first, to provide a recording device which shall indicate the starting and stopping of a machine and the time of its operation. Second, 15 to provide a recording device embodying the above advantages which is simple in structure and operation and not likely to get out of repair.

Further objects, and objects relating to 20 structural details, will definitely appear from the detailed description to follow.

I accomplish the objects of my invention by the devices and means described in the following specification.

25 The invention is clearly defined and pointed out in the claims.

A structure embodying the features of my invention is fully illustrated in the accompanying drawing forming a part of this 30 specification, in which—

Figure 1 is a front elevation of my improved registering or recording instrument. Fig. 2 is a vertical section through the case, taken on a line corresponding to line 2 2 of 35 Fig. 1, a motor being shown in conventional form connected therewith. Fig. 3 is an enlarged detail section taken on a line corresponding to line 3 3 of Fig. 1, showing the structure and arrangement of the marker.

40 Fig. 4 is an enlarged detail sectional view taken on a line corresponding to line 4 4 of Fig. 1, showing structural details. Fig. 5 is a detail showing the slip connection for the cord H' to the marker carrying arm G.

45 In the drawing the sectional views are taken looking in the direction of the little arrows at the ends of the section lines, and similar letters of reference refer to similar parts throughout the several views.

50 Referring to the lettered parts of the drawing, I provide a suitable frame or casing A for the operating mechanism, which is preferably provided with a glazed door, as A', so that the mechanism—particularly

the record sheet C—is visible from the outside. A suitable clock mechanism, as B—which is here shown in conventional form as a spring driven clock mechanism—is provided. It is preferable that this clock mechanism should revolve the shaft B' once an hour. A record sheet C is detachably secured upon the shaft B' by a suitable thumb-nut b (see Fig. 4), so that the record sheet is revolved with the shaft. This record sheet is preferably circular in form and is ruled to form radial minute spaces, there being sixty lines upon the sheet. The sheet is also preferably provided with radially arranged hour spaces and hour indicating characters, the sheet herein shown having hour indicating characters from 6 a. m. to 8 p. m.

The record sheet is held in position for the marker by a bracket-like support D arranged to the rear thereof. An arm D' 75 coacts with the rest D in preventing the vibration of the sheet. Bracket-like guides D'' are also provided for the sheet. These guides are provided with slits into which the edge of the record sheet projects. 80

Arranged below the clock mechanism in the casing is a bracket-like frame E. Arranged in this frame E is an electro-magnet E' and the frame F for the armature F'. The frame F is pivoted to the frame E by 85 the pivot screws f. The armature is held normally out of contact with the magnets by a spring, as f'. A set screw f'' is provided for limiting the upward movement of the armature carrying frame. 90

The pivoted marker carrying arm G is mounted upon the bracket E on a suitable pivot, as the screw g''. A spring g'' puts tension on the arm G to hold it normally in toward or against the record sheet or disk, 95 and also tends to hold the same radially outward, as is hereinafter described. The armature frame F is pivoted at f on the bracket E, the axis of the pivots being at right angles to the pivot g'', and this frame is arranged to press against the arm G to lift it away from the face of the record sheet or disk and permit the same to swing freely radially across the record disk. Upon the upper end of the arm G I secure the marker, 100 which preferably consists of the fluid receptacle, having a spout-shaped pen G'' thereon. This is preferably made of one piece 105

of sheet metal. A wick is arranged in the pen and depends into the receptacle. I preferably use a hygroscopic writing fluid, although, of course, any suitable writing fluid may be used. The receptacle G' is detachably secured to the arm G by means of a ring G''' . This ring G''' is clamped on the arm G by the wedge g (see Fig. 3).

When the frame F is rocked rearwardly 10 on its pivots f by the magnet, this withdraws the frame F from the marker arm G . The pen is thrown into contact with the record sheet by the action of the spring g'' . As the record sheet is revolved by the clock 15 mechanism, the record is made by the marker contacting with the disk while the disk is in motion, and the marker arm, by the mechanism hereinafter described, is drawn gradually to the center of the disk, making a 20 long record by a spiral line on a single sheet. This radial movement of the marker I preferably accomplish by means of a cord H' , which is secured to the arm G by a spring clip h , the cord being wrapped around the 25 shaft B' of the clock mechanism, so that, as the shaft is revolved the arm is drawn inwardly thereby. This makes the record in the form of a spiral, with breaks therein whenever the machine whose operation is 30 being recorded, is stopped. A weight, as H , is suspended from the cord H' to apply sufficient tension so that the cord will not slip on the shaft.

The hour spaces marked on the record 35 sheet correspond to the inward movement of the arm G during each revolution of the shaft, so that the record lines properly correspond with the hour. A spring g'' holds the arm normally outward against the pull 40 of the cord H' .

The spring clip h is provided for fastening the cord H' to the arm G , so that in the event of the clock not being stopped when the arm reaches the limit of its inner movement, the clip will release the arm so that 45 no damage will be done to the apparatus.

The magnet E' is provided with an electrical connection to the machine, the operation of which is to be recorded. I have indicated in conventional form an electric 50 motor I as being the machine, the operation of which is to be recorded, and i indicates the switch for turning the current off and on.

In the structure illustrated, I show the 55 magnet connected direct to the motor, so that when the current is on the motor it will also be on the magnet. It is evident, however, that other connections might be made, 60 the object being to electrify the magnet E' when the machine is started. When my improved recording device is used in connection with a mechanically operated machine, it will be necessary to provide a battery or 65 other electrical supply. As the arrange-

ment of this will readily appear to one skilled in the art, I have not herein illustrated the same. By thus arranging and connecting my improved recording device to the machine, the operation of which it is desired to record, when the machine is started the recording pen will be thrown into contact with the record sheet by means of the magnet and held there until the machine is stopped, recording the period of time of the 70 operation of the machine and indicating all stops. This can be quickly seen at a glance from an inspection of the record sheet.

I preferably arrange the recording device in the office or other convenient place for the 80 inspection of the proper persons. It is evident, however, that it may be arranged in any position desired.

By my improved recording device, the 85 exact time of starting a machine is indicated, and also all stops, as stated. This furnishes complete data for the computation of cost on piece work, tool charges, tool depreciation, etc. It also enables the determination of the merits of each operator. 90

It is intended that the clock shall be stopped and started at the beginning and end of each day, a brake, as J , being provided for this purpose. This brake is arranged to engage the clock mechanism. 95 However, this may be used or not, as desired.

My improved recording device requires 100 practically no attention other than the changing of the record sheets. If it is desired, the sheets may be filed, thereby furnishing a complete record of the work of any particular machine.

I have illustrated and described my improved recording device in detail in the 105 form preferred by me on account of its structural simplicity and economy. I am aware, however, that it may be varied very greatly in structural details without departing from my invention, and I claim the same 110 specifically, as here illustrated, as well as broadly.

Having thus described my invention, what I claim as new and desire to secure by Letters Patent, is:

1. The combination with a machine, the operation of which it is desired to record, of a 115 clock mechanism; a stop device for said clock mechanism; an hourly revolving shaft driven thereby, having a record sheet thereon ruled to form radial minute spaces and radially arranged hour spaces, said hour spaces being provided with proper designating numerals; a support for the said record sheet, arranged at the rear thereof; guides for said record sheet having slits adapted to receive the edge thereof; an electro-magnet; an armature; a pivoted carrying frame therefor; a spring for holding said armature normally out of contact with said electro-magnet; an arm ar- 130

- ranged in contact with said armature carrying frame; a marker carried thereby arranged to contact with the record sheet when the armature carrying frame is actuated; a 5 cord for moving said marker carrying arm laterally, connected thereto by a spring clip, said cord being wrapped about the said shaft; a weight for applying tension to said cord; a spring for holding said marker carrying arm normally outward; and electrical connections for said electro-magnet to said machine, whereby said magnet is electrified when said machine is in operation, all coacting for the purpose specified.
- 10 2. The combination with a machine, the operation of which it is desired to record, of a clock mechanism; an hourly revolving shaft driven thereby, having a record sheet thereon ruled to form radial minute spaces and radially arranged hour spaces, said hour 15 spaces being provided with proper designating numerals; a support for the said record sheet, arranged at the rear thereof; guides for the said record sheet having slits adapted to receive the edge thereof; an electro-magnet; an armature; a pivoted carrying frame therefor; a spring for holding said armature normally out of contact with said electro-magnet; an arm arranged in contact 20 with said armature carrying frame; a marker carried thereby arranged to contact with the recording sheet when the armature carrying frame is actuated; a cord for moving said marker carrying arm laterally, connected thereto by a spring clip, said cord being wrapped about the said shaft; a weight for applying tension to the said cord; a spring for holding said marker carrying arm normally outward; and electrical 25 connections for said electro-magnet to said machine, whereby said magnet is electrified when said machine is in operation, all coacting for the purpose specified.
- 30 3. The combination with a machine, the operation of which it is desired to record, of a clock mechanism; a stop device for said clock mechanism; an hourly revolving shaft driven thereby, having a record sheet thereon ruled to form radial minute spaces and radially arranged hour spaces, said hour 35 spaces being provided with proper designating numerals; an electro-magnet; an armature; a pivoted carrying frame therefor; a spring for holding said armature normally out of contact with said electro-magnet; an arm arranged in contact with 40 said armature carrying frame; a marker carried thereby arranged to contact with the record sheet when the armature carrying frame is actuated; a cord for moving said marker carrying arm laterally, connected thereto by a spring clip, said cord being wrapped about the said shaft; a weight for applying tension to said cord; a spring for holding the said marker carrying arm normally outward; and electrical connections for said electro-magnet to said machine, whereby the said magnet is electrified when said machine is in operation, all coacting for the purpose specified.
- 45 3. The combination with a machine, the operation of which it is desired to record, of a clock mechanism; a stop device for said clock mechanism; an hourly revolving shaft driven thereby, having a record sheet thereon ruled to form radial minute spaces and radially arranged hour spaces, said hour 50 spaces being provided with proper designating numerals; an electro-magnet; an armature; a pivoted carrying frame therefor; a spring for holding said armature normally out of contact with said electro-magnet; an arm arranged in contact with said armature carrying frame; a marker carried thereby, arranged to contact with the record sheet when the armature carrying frame is actuated; a cord for moving said marker carrying arm laterally, connected thereto by a spring clip, said cord being wrapped about the said shaft; a weight for applying tension to said cord; a spring for holding said marker carrying arm normally outward; and electrical connections for said electro-magnet to said machine, whereby the said magnet is electrified when said machine is in operation, for the purpose specified.
- 55 6. The combination with a machine, the operation of which it is desired to record, of a clock mechanism; an hourly revolving shaft driven thereby, having a record sheet thereon; an electro-magnet; an armature; a pivoted carrying frame therefor; an arm arranged to contact with said armature carrying frame; a marker carried thereby arranged to contact with the record sheet when the armature carrying frame is actuated; a cord for moving said marker carrying arm laterally, connected thereto by a spring clip, said cord being wrapped about the said shaft; a weight for applying tension to said cord; a spring for holding said marker carrying arm normally outward; and electrical connections for said electro-magnet to said machine, whereby the said magnet is electrified when said machine is in operation, all coacting for the purpose specified.
- 60 7. The combination with a machine, the operation of which it is desired to record, of a clock mechanism; an hourly revolving shaft driven thereby, having a record sheet thereon; an electro-magnet; an armature; a pivoted carrying frame therefor; an arm arranged to contact with said armature carrying frame; a marker carried thereby arranged to contact with the record sheet when the armature carrying frame is actuated; a cord for moving said marker carrying arm laterally, wrapped about the said shaft; a weight for applying tension to said cord; a spring for holding said marker carrying arm normally outward; and electrical connections for said electro-magnet to said machine, whereby the said magnet is electrified when said machine is in operation, all coacting for the purpose specified.
- 65 8. The combination with a machine, the operation of which it is desired to record, of a clock mechanism; an hourly revolving shaft driven thereby, having a record sheet thereon; an electro-magnet; an armature; a pivoted carrying frame therefor; an arm arranged to contact with said armature carrying frame; a marker carried thereby arranged to contact with the record sheet when the armature carrying frame is actuated; a cord for moving said marker carrying arm laterally, wrapped about the said shaft; a weight for applying tension to said cord; a spring for holding said marker carrying arm normally outward; and electrical connections for said electro-magnet to said machine, whereby the said magnet is electrified when said machine is in operation, all coacting for the purpose specified.

chine whereby said magnet is electrified when said machine is in operation, for the purpose specified.

7. The combination of a machine, the operation of which it is desired to record, of a clock mechanism; an hourly revolving shaft driven thereby, having a record sheet thereon ruled to form radial minute spaces and radially arranged hour spaces, said hour spaces being provided with proper designating numerals; an electro-magnet; an armature; a pivoted carrying frame; an arm arranged to contact with said armature carrying frame; a marker carried thereby arranged to contact with the record sheet when the armature carrying frame is actuated; a cord for removing said marker carrying arm laterally, wrapped about the said shaft; and electrical connections for said electro-magnet to said machine, whereby said magnet is electrified when said machine is in operation, for the purpose specified.

8. The combination with a machine, the operation of which it is desired to record, of a clock mechanism; an hourly revolving shaft driven thereby, having a record sheet thereon; an electro-magnet; an armature; a pivoted carrying frame therefor; an arm arranged to contact with said armature carrying frame; a marker carried thereby, arranged to contact with the record sheet when the armature carrying frame is actuated; a cord for moving said marker carrying arm laterally, wrapped about the said shaft; and electrical connections for said electro-magnet to said machine whereby said magnet is electrified when said machine is in operation, for the purpose specified.

9. The combination with a machine, of a clock mechanism; an hourly revolving shaft driven thereby, having a record sheet thereon ruled to form radial minute spaces and radially arranged hour spaces, said hour spaces being provided with proper designating numerals; an electro-magnet; an armature; a pivoted carrying frame therefor; an arm controlled by said armature carrying frame; a marker carried thereby arranged to contact with the record sheet when the armature carrying frame is actuated; connections for said arm to said clock mechanism whereby said arm is shifted; and means for electrifying said electro-magnet upon the starting of the machine, for the purpose specified.

10. The combination with a machine, of a clock mechanism; an hourly revolving shaft driven thereby, having a record sheet thereon; an electro-magnet; an armature; a pivoted carrying frame therefor; an arm controlled by said armature carrying frame; a

marker carried thereby arranged to contact with said record sheet when the armature carrying frame is actuated; connections for said arm to said clock mechanism whereby said arm is shifted; and means for electrifying said electro-magnet upon the starting of said machine, for the purpose specified.

11. The combination with a machine, of a clock mechanism; an hourly revolving shaft driven thereby, having a record sheet thereon ruled to form radial minute spaces and radially arranged hour spaces, said hour spaces being provided with proper designating numerals; an electro-magnet; an armature; a pivoted carrying frame therefor; an arm controlled by said armature carrying frame; a marker carried thereby arranged to contact with the record sheet when the armature carrying frame is actuated; and means for electrifying said electro-magnet upon the starting of said machine, for the purpose specified.

12. The combination with a machine, of a clock mechanism; a record sheet carrier actuated thereby; an electro-magnet; an armature; a marker actuated by said armature; connections for said marker to said clock mechanism whereby said marker is shifted on said record sheet; and means for electrifying said magnet upon the starting of said machine, for the purpose specified.

13. The combination with a machine, the operation of which it is desired to record, of a clock mechanism; an hourly revolving shaft driven thereby, having a record sheet thereon ruled to form minute spaces and radially arranged hour spaces, said hour spaces being provided with proper designating numerals; a marker; an electrical device for actuating said marker; a cord for moving said marker laterally, wrapped about the said shaft; and electrical connections for said marker actuating device to said machine, for the purpose specified.

14. The combination with a machine, the operation of which it is desired to record, of a clock mechanism; an hourly revolving shaft driven thereby, having a record sheet thereon; a marker; an electrical device for actuating said marker; a cord for moving said marker laterally, wrapped about the said shaft; and electrical connections for said marker actuating device to said machine, for the purpose specified.

In witness whereof, I have hereunto set my hand and seal in the presence of two witnesses.
